UNITED STATES PATENT OFFICE.

WILLIAM F. PURCELL, OF HORNELL, NEW YORK.

AUTOMATIC TRAIN-STOPPING APPARATUS.

1,109,463.

Specification of Letters Patent.

Patented Sept. 1, 1914.

Application filed February 15, 1913. Serial No. 748,656.

To all whom it may concern:

Be it known that I, WILLIAM F. PURCELL, a citizen of the United States, residing at Hornell, in the county of Steuben and State 5 of New York, have invented new and useful Improvements in Automatic Train-Stopping Apparatus, of which the following is a specification.

This invention relates to improvements in 10 train stopping apparatus and has particular application to an automatic train stopping system.

In carrying out the present invention it is my purpose to provide an automatic train 15 stopping apparatus which may be used conjointly with the road signal system and which will be controlled by and operated from such system so that should the engineer of a train through carelessness or 20 otherwise neglect to read the signal set to "danger", the train will be automatically brought to a stand-still before entering the danger zone or protected track area.

It is also my purpose to provide an automatic train stopping system which will embrace the desired features of simplicity, 25 efficiency and durability and which may be installed and maintained at a minimum expense.

Furthermore, it is my intention to provide 30 an automatic train stopping system or apparatus which will operate effectively irrespective of prevailing weather conditions and which will be constructed in such manner as 35 to relieve the road signal mechanism of any unnecessary strain or weight incident to the connections between the train stopping apparatus and the signal system.

With the above recited objects in view 40 and others of a similar nature the invention consists in the construction, combination and arrangement of parts set forth and falling within the scope of the appended claims.

In the accompanying drawings:—Figure 45 1 is a view in side elevation of a locomotive and "semaphore standard or post" showing the relative positions of the train-carried portion and signal controlled portion of the apparatus. Fig. 2 is an end view of the locomotive showing the relative positions of the parts at right angles to that illustrated in Fig. 1. Fig. 3 is an enlarged fragmentary 50 side elevation of the locomotive showing the train-carried portion of the apparatus on an enlarged scale. Fig. 4 is a view in elevation of a detail of the invention. Fig. 5

is a cross sectional view on the line 5—5 of Fig. 4. Fig. 6 is a view in elevation of a semaphore post and signal blade showing a modified form of the signal controlled 60 portion of the apparatus.

In carrying my invention into practice I wish it to be understood that my improved 65 train stopping apparatus may be used in conjunction with any form of signal system whether it be automatic or train controlled lock type or of that character which is manually controlled.

Referring now to the accompanying drawings in detail, A indicates the track-way 70 over which is designed to travel a locomotive B, while C designates a semaphore standard or post mounted to one side of the track structure and having pivoted thereto adjacent to the upper end thereof 75 a signal or semaphore arm 1. In the present instance, this arm is in the nature of a three position signal, that is to say, capable of moving to three positions so as to indicate "clear," "caution" and "danger." 80

In this form of my invention the train-carried portion of the automatic train stopping apparatus includes the train line air pipe 2 of the air brake system to which is tapped a pipe 3 extending upwardly along- 85 side of the forward end of the cab of the engine and terminating in an outwardly and downwardly projecting nipple 4 equipped with a valve 5 by means of which the train line air pressure may be reduced 90 to effect an application of the brakes to the wheels as will be readily understood. Connected to the stem of the valve 5, which latter may be of any appropriate construction, is a handle 6 to the free end of which 95 is pivotally connected the forked extremity 7 of an angular operating rod 8 passed through a slot 9 in the wall of the locomotive cab and terminating within such cab and a handle 10. In addition to the valve 100 5 the pipe 3 is preferably provided with a manually operable valve 11 disposed between the valve 5 and the train line air pipe 2 and adapted to cut off communication between the atmosphere and the train 105 line air pipe when the valve 5 is open, the valve 11 being employed only under certain circumstances as will presently appear.

Normally the handle 6 of the valve 5 is extended outwardly of or at right angles 110 to the cab of the locomotive and is disposed in a plane coincident with that of

the nipple 4, the rod 8 being operated to throw the handle into this position.

The signal controlled portion of the apparatus embodies an arm 12 pivoted between its ends upon a pin 13 carried by a collar 14 surrounding the standard C and suitably secured thereto at a point below the semaphore arm 1. This rod 12 lies in a plane at right angles to that of the track-way and has connected to the outer end thereof a vertical arm 15, while slidably disposed upon the inner end of the rod is a counterweight 16 designed to be held in any desired adjusted position by means of a set screw 17 carried thereby and adapted to bind against the adjacent part of the rod. In the caution and clear positions of the signal blade, as indicated by the dotted lines in Fig. 1, the outer end of the rod 12 is in an up position and out of the path of movement of the handle 6 of the valve 5 controlling the train line air pipe, while when the signal blade or arm is moved to the danger position the rod 12 is thrown to a position at right angles to the standard and the arm 15 carried thereby in the path of movement of the handle 6 of the train line air pipe controlling valve, the counterweight 16 holding the rod 12 in an inoperative position in the clear and caution positions of the semaphore arm, while by means of a cord 18 or other suitable flexible element connecting the inner end of the rod 12 with the free end of the semaphore blade, the rod is moved to an operative position when the blade is thrown to danger.

The valve handle 6 at the point which is contacted by the arm 15 when the rod 12 is in operative position, is flattened as at 19 and has lugs 20 formed on one face thereof to provide a guide-way and hold a piece of frangible or other destructible material, such for instance as glass 21. The purpose of this construction is to enable the authorities to determine when the engineer has permitted his train to pass a signal set at danger.

From the above description taken in connection with the form of apparatus illustrated in Figs. 1 to 5, inclusive, the construction and mode of operation will be readily apparent.

Assuming the semaphore blade to be set at danger as illustrated in Fig. 2 and the rod 12 in operative position, that is to say, at right angles to the standard C and a train is approaching the signals, it will be seen that should the engineer neglect to read the signal, the arm 15 will be contacted by the handle 6 of the valve 5, whereby the latter will be opened to vent the train line air pipe thereby effecting an application of the brakes to the wheels so that the train will be brought to a stand-still before entering the danger zone. Should a train be stalled with-

in the protective track area, the latter being determined by the distance between the signals, and the engineer of such stalled train desire the assistance of a train approaching the block or protected area of track, the engineer of the approaching train may by manipulating the valve 11 cut off communication between the train line air pipe and the atmosphere and subsequently operate the rod 8 to move the valve handle 6 and so open the valve 5 thereby throwing the valve handle out of the way of the arm 15 on the rod 12. Thus the train may enter the protected track area against the signal, without having the train-carried portion of the stopping apparatus operated. By means of the counterweight 16 it will be noted that a loose connection may be established between the semaphore blade and the rod 12, the counterweight acting at all times to hold the rod in inactive position while the loose connection, effected in the present instance by the cord 18, acts to throw the rod to an operative or active position only when the signal blade is at danger. Thus a rigid or fixed connection between the signal blade and the rod 12, and the disadvantages inherent in such a connection are avoided.

Fig. 6 discloses a modified construction of the signal controlled portion of the stopping apparatus. In this figure I have illustrated the respective portions of my invention as operable from a semaphore or signal blade movable in the upper quadrant, in contradistinction to a signal blade movable in the lower quadrant as disclosed in Figs. 1 to 5, inclusive. In this case the signal blade 1 is in the form of a three-position signal movable in the upper quadrant and the flexible connection 18 between the signal and semaphore blade 1 and the rod 12 is passed over a sheave 22 journaled in the yoked end of a bracket 23 suitably connected to the signal standard C at a point below the rod 12. Thus when the signal blade is in clear or caution position, the arm 12 is held positively against movement to operative position, while, on the contrary, when the signal blade assumes the danger position, the arm 12 moves to an operative position, that is to say, to a position to dispose the arm 15 in the path of movement of the valve handle 6. The counterweight 16 in this instance is utilized as a counterbalance to compensate for the differences in the distances between the fulcrum point of the rod 12 and the outer end thereof and between such point and the inner end.

From the above description taken in connection with the accompanying drawings, the construction, operation and manner of employing my invention will be readily apparent. It will be seen that I have provided a train stopping apparatus which is entirely automatic in action and which may be ren-

dered inoperative when conditions warrant and further, it will be noted that the connections between the signal blade and the signal controlled portion of the apparatus are such 5 as to relieve the signalling system of any unnecessary work or strain.

While I herein have shown and described certain particular forms of my invention by way of illustration I wish it to be understood 10 that I do not confine myself to the precise details of construction and the relative arrangement of the parts as herein described and delineated, as modifications and variations may be made within the scope of the 15 claims without departing from the spirit of the invention.

I claim:

In automatic train stopping apparatus, the combination with the train line air pipe of 20 the brake system, of a valve connected in said pipe and adapted when open to bleed the same, a handle on said valve, an operat-

ing rod having one extremity connected to said handle and passed through the wall of the locomotive cab, a handle on the cab end 25 of said rod within the reach of the engineer whereby said rod may be actuated to open said valve manually, a second valve connected in said pipe and operable to cut off communication between the train line air pipe 30 and the atmosphere when the first valve is open, means operable automatically to engage the handle of said first valve to open the latter, and means on said handle and adapted to be contacted by said last means to 35 indicate that the valve has been opened automatically.

In testimony whereof I affix my signature in presence of two witnesses.

WILLIAM F. PURCELL.
